HOLDER FOR COSMETICS

Rosalia Zumpano Sarff, New York, N. Y.

Application February 11, 1947, Serial No. 727,869

1 Claim. (Cl. 132—83)

1

This invention is an improvement in holders or casings for cosmetic substances, particularly rouge or face powder and the like; and adapted further to contain a device or implement by which the beautifying preparation can be employed in the required way when needed.

An object of the improvement is to provide a neat and compact holder divided into compartments to receive the cosmetic and the implement by which it is administered to the owner's features; and so designed as to include a mirror to facilitate the use thereof.

Other objects and advantages of the invention are set out in the following specification and the novel features are precisely defined in the appended claim. But this disclosure is by way of example only, and the construction showing the best form of the invention now known to me can be altered in various ways without deviating from the principle of the invention, or omitting any of the essential parts.

On the drawings:

Figure 1 is a front view of an embodiment of my invention, showing a casing with a cover in open position.

Figure 2 is a side elevational view of a cosmetic brush holder for insertion into the casing.

Figure 3 is a longitudinal section of said holder with the brush ready for operation.

Figure 4 shows the brush holder in section.

Figure 5 is a section on line 5—5 of Figure 1.

The body 1 of the casing or holder in the form shown on Figures 1 to 5 has a hinged lid or closure 2, with a reflecting surface 3 on the inner face to act as a mirror. In the body just below the upper edge is a horizontal partition 4 and under this partition is a large compartment 5, open at one end of the casing and intended for the lodgment of a brush holder 9 having a flanged head 10, which abuts the exterior of the casing 1 when the holder or handle 9 is inserted into the compartment 5.

The head 10 of the member 9 has a cavity or recess on its inner face to mount therein a cylindrical element or sleeve 11. The end of the element fits this recess tightly to hold against rotation in the head 10, and telescoping into the open outer end is a brush carrier 12 with bristles 13 in the extremity thereof. The carrier or brush tip 12 is cylindrical over part of its length, but tapers somewhat towards the bristles 13 and adjacent its inner extremity it mounts a cross-pin 14, which projects into a longitudinal slot 15 in the sleeve 11. In the head 10 and surrounding the sleeve 11 is an annular shoulder 16,

2

against which abut the ends of a pair of tubular sections 17 and 18, the latter enveloping the former, and the ends thereof engaging the shoulder 16 surrounded and covered by the rim 19 of the head. The inner section has a spiral slot 20 into which the pin 14 projects but this slot is concealed by the outer section or element 18. The two sections fit together tightly enough, or are otherwise connected so that rotation of the section 18 will turn the section 17. These two sections can be rigidly connected by working a bead 21 around the rim of the section 17, and overturning the rim of the section 18 against said bead.

Therefore, by rotation of the section 18 with the fingers, the slot 20 pushes the brush carrier 12 out or pulls it back. When the bristles are withdrawn into the end of the sleeve 11, the brush holder or handle 9 can be put into the casing as shown in Figure 5. When taken out, the handle can be manipulated to cause the bristles to project, to be dipped into the contents of the cells tray 4.

The casing 1 is round, and it flares or expands 25 at one end 22, which is closed by the inside partition 4. This makes an upper compartment for a small round tray 23 to contain a cosmetic preparation. The round holder 9, head 10 and rim 19 are inserted at the opposite end of the casing. The rim part makes a shoulder at the head and always fits the casing 1 snugly so that the brush and handle will not drop out. The large flaring end 22 is closed by a cover or lid 2, with an inside mirror surface 3. The closure 2 30 co-operates with a catch consisting of a spring projection 26 with a projection 27 on the body of the casing to engage a retaining element 28 on the inside of the rim of the closure. The projection 26 is worked by a small protuberance 35 30, extending through a slot 30 in the rim of the closure. Both the projection 26 and the protuberance 29 are attached to a spring strip 31 on the inside of the rim of the casing, held 40 in place by a rivet 32.

The casing is therefore attractive as well as efficient. The casing and mirror are held in one hand and the brush handle in the other, for use when desired; and the invention is well calculated to serve its purpose in a most satisfactory manner.

Figure 4 shows the brush carrier 12 with the bristles in its tapered front end separated from the casing, and includes the cross pin 14 which 55 engages slots 15 and 20.

Having described my invention, what I believe to be new is:

A casing for cosmetic use, having one end open and the other end enlarged and flaring in shape and terminating in a cylindrical rim, a transverse partition in said flaring end surrounded by said rim, a tray in said end separated by the partition from the remainder of the interior of said casing, a closure hinged to the rim of said flaring end, said closure having an inside reflecting surface, a spring catch mounted inside the rim of said flaring end for retaining the closure, the catch having a projection and the rim an opening containing said projection to enable the catch to be operated, a retaining element in the closure to be engaged by the catch, and a handle carrying a brush at one end and received in the opposite end of the casing, said handle having a shouldered head for engaging the open end of the casing.
